UNITED STATES PATENT OFFICE.

PHILIP LAUTER, OF NEW YORK, N. Y., ASSIGNOR TO POLYMET MANUFACTURING CORPORATION, A CORPORATION OF NEW YORK.

EXTENSION CONNECTER.

Application filed August 10, 1925. Serial No. 49,224.

The present invention relates generally to extension connectors adapted for use in the electrical art and more particularly to devices used to join pairs of wires in order that the flow of current may be continuous and uninterrupted and to hold the same securely in position. Such devices are used generally in house wiring, connectors for electric lamps, fire places, telephony, or in fact whenever it is desired to join pairs of wires with a good electrical connection.

Such uniting of pairs of wires has been accomplished by intertwisting the ends and taping, but such an expedient is a makeshift at best and very uncertain and unsightly as well as presenting considerable risk of short circuiting with consequent fire hazard. Certain devices used for this purpose have been objectionably clumsy and unsightly as well as uncertain of operation and awkward to install in the line. Such devices also are not capable of joining wires terminating in metal tips, being merely designed to join the bare metal ends. The use of metal tips has become increasingly popular as being much neater, safer and more convenient to handle.

One of the objects of my invention is to provide a small, neat device whereby the ends of pairs of wires may be conveniently joined irrespective to whether such ends are merely bared or are provided with metal tips.

Another object of my invention is to join such wires with a positive electrical connection, such connection being formed by what is called a "rubbing" contact.

A further object of my invention is to provide a device of such character that the connection between the pairs of wires may be of a temporary nature, and readily detachable at will, or of a semi-permanent form.

Another object of my invention is the provision of means to securely hold the wires in position and prevent accidental dislodgment of such wires.

A further object of my invention is to so construct the device that stresses or strains on the pairs of wires, which would ordinarily tend to sever the connection are taken up on heavy posts provided for the purpose. As a matter of fact such strains tend to cramp the metal tips against the devices in such a way that the connection is stronger while such strains are applied.

Another object is to provide a neat, simple and inexpensive device which is attractive in appearance, positive in operation and completely encloses the connection in insulated material so as to be safe to use and handle and prevent any current leakage. My device should last indefinitely as no part is subject to strain or excessive wear.

With these and other objects in view, to be more fully set forth hereinafter, the invention consists in the novel construction, combination of elements and arrangement of parts which will be exemplified in the operation and construction herein described in the following specification and illustrated in the accompanying drawings.

The invention will first be described in connection with the accompanying drawings, wherein similar reference characters are used to designate corresponding parts throughout the several views, and more specifically defined and indicated in the appended claims.

Attention is directed to the drawings in which:

Fig. 1 is a perspective view of my invention showing the method of crossing the wires in forming the connection.

Fig. 2 is an end view with the wires omitted.

Fig. 3 is a plan view of the lower half, with a pair of wires in position to show the electrical connection.

Fig. 4 is a sectional view, on the line 4-4 of Fig. 3, with both halves bolted together and the wires omitted.

Fig. 5 is a view similar to Fig. 3 but of a modification and with the wires omitted.

Fig. 6 is a plan view with a portion of the cover broken away to show the modification with two types of wire terminals in position, and,

Fig. 7 is an elevation of the modification with the wires omitted.

My device is preferably molded from suitable insulating material such as hard rubber, porcelain or any other of the molded insulating materials. Further my extension connector is made in two parts as 1 and 2, each an exact replica of the other and secured snugly together as by slotted bolts 3 and nuts 4 located within the decorative countersunk portions 5, Figs. 1 and 4. Each of the portions 1 and 2 has diverging bores 6, 7, 8, and 9 formed therein to receive the

wire terminals as shown in Fig. 3. Also the 10 depressions or recesses 10 and 11 so as to form posts 12 and 13 for a purpose about to be disclosed. The electrical connectors 14 and 15 of suitable current conducting material, having a springy nature, are snugly carried in slots in casings 1 and 2 as is clearly shown in Fig. 3. The end portions 16 and 17 are curled backward so as to form springy contact points to make wiping contact with the wire ends as with the metal tips 18 and 19 when these tips are forced home in the bores 8 and 9, (see Fig. 3). The contact points 17 are in normal position 15 while the points 16 are in spring or contact making position, the casing being provided with the recesses 20 to freely permit of this movement of the contact points. The shoulders 21 formed on the casing prevent the opening out of the contact points and assists in holding them normally in position.

In utilizing my connector the wires 22 and 23 terminating in the metal tips 19 and 18 respectively are crossed in the recess 11 and the metal tips are forced home in the bores 9 and 8 respectively. The wires 24 and 25 are likewise crossed in recess 10 and their metal tips forced home in the bores 7 and 6 respectively. The electrical circuit is now complete passing from the wire 22 tip 19 connector 15 tip in bore 7 and outwire 24. Thus it will be seen that the current enters and leaves the device through wires located conveniently on the same side of the device.

35 A strain on the wires 22 and 23 in a direction away from the device is taken up almost entirely on the rugged post 13, because of the crossing of the wires within the recess 11. What little of the strain may be conveyed to the tips 18 and 19, merely serves to cramp them all the tighter within their bores 8 and 9. Thus a strain, as above, is taken up by the strong body of my device and the electrical connection is undisturbed. 40 While in the foregoing description I have briefly described the means which prevent the wires 22 and 23 from being dislodged, it is obvious that the wires 24 and 25 are also firmly and securely held in position as 45 the means for holding said wires are a duplicate of holding means for the wires 22 and 23. By utilizing my connector the wiring can be made of considerable length and the connector will make a very neat and attractive appearance and firmly hold the wires together without fear of the same being accidentally pulled apart.

As a modification Figs. 5 to 7, I provide additional bores 26 and 27, in the sides of 50 my device, loosely within which are located headless slotted bolts 28 and 29 threaded through holes in connectors 14 and 15 and with their rounded ends bearing on the underside of the contact points. In this construction the shoulders 21 are omitted as

it is desirable to screw the bolts so as to force the contact points towards the side of the bore so as to securely pinch the bared end of the wire or metal tip within the device. With this construction it is possible 70 to leave the contact point in springy condition, as for a temporary connection, as with tip 30, Fig. 6 or the bolt may be screwed home, within the bore, to force the contact point against the wire end for a semi-permanent connection. This latter result is illustrated as applied to the bared end of wire 75 31 in Fig. 6.

In accordance with the provisions of the patent statute, I have described my invention together with the construction which I now consider to represent the best embodiment thereof, but I desire it understood that my invention is not confined to the particular form shown and described, the same being 80 merely illustrative, and that the invention can be carried out in other ways without departing from the spirit of my invention, and therefore, I claim broadly to employ all equivalent instrumentalities coming within 85 the scope of the appended claims, and by means of which objects of my invention are attained, and new results accomplished, as herein set forth, as it is obvious that the particular embodiments herein shown and described are only some of many that can be employed to attain these objects and accomplish these results.

Having now described my invention, what I claim and desire to secure by Letters Patent, is:—

1. In an attachment plug, a pair of insulating plates, each having grooves radiating from the center to the edge and so arranged that when said plates are superimposed, the grooves of one will coincide with the grooves of the other to form converging cord tip receiving passages, and a partition having T-shaped ends and contact springs clamped around said ends to contact with cord tips 110 positioned in said passages.

2. In an attachment plug, a pair of insulating plates each having grooves radiating from the center to the edge and so arranged that when said plates are superimposed the grooves of one will coincide with the grooves of the other to form converging cord tip receiving passages, and a partition having T-shaped ends, and C-shaped contact springs clamped around said ends to contact with cord tips positioned in said passages.

3. In an attachment plug, a pair of insulating plates each having grooves in one of its faces, said grooves being so arranged that when said plates are superimposed the grooves in one will coincide with the grooves of the other to form cord tip receiving passages, a narrow recess formed in said plates to retain a C-shaped spring of flat thin 130

- metal, the opposite ends of said spring extending into opposite passages to form resilient contacts for cord tips positioned in said passages, and means engaging said 5 spring to cause said spring to releasably lock the cord tips against the walls of passages.
4. In an attachment plug, a pair of insulating plates each having grooves in one of its faces, said grooves being so arranged that 10 when said plates are superimposed the grooves in one will coincide with the grooves of the other to form cord tip receiving passages, a narrow recess formed in said plates to retain a C-shaped spring of flat thin metal, the opposite ends of said spring extending into opposite passages to form resilient contacts for cord tips positioned in said passages, and pressure screws engaging the ends of said spring to cause said spring to be forced against the cord tips to releasably lock the cord tips against the wall of 15 said passages.
- 20

This specification signed this 31 day of July, 1925.

PHILIP LAUTER.
